STAPLING MACHINE

Seraphine F. Bauwens, Chicago, Ill., assignor to
Bauwens Machine Company, Inc.

Application March 23, 1939, Serial No. 263,636

11 Claims. (Cl. 1-3)

The invention relates to improvements in stapling machines and has particular utility as applied to a machine for shaping a ribbon or band in the form of an accurately dimensioned bow and stapling the band to hold it in such configuration.

One object of the present invention is to provide a machine of the type set forth which is rugged in construction, economical to manufacture, and so simple to manipulate that it may be used efficiently by even a comparatively unskilled operator.

A further object of the invention is to provide a machine for stapling a band or ribbon, such as is used, for example, on men's hats, in a bow form while utilizing a minimum of ribbon and with all of the staples neatly arranged in concealed positions.

Another object of the invention is to provide a stapling machine capable of accurately and precisely determining the length of the various parts of a decorative bow formed in a ribbon or band and for stapling the material to hold it in such configuration.

Still another object of the invention is to provide a stapling machine embodying a novel staple clinching mechanism of such character that the legs of the staples are clinched flat against the material to which they are applied without any unsightly bowing or bulging. By clinching the staples with such a mechanism they are particularly adapted for use in a decorative bow of ribbon or the like where any bulging of the staples is especially undesirable although they may, of course, be used for other purposes.

Further objects and advantages of the invention will become apparent as the following description proceeds taken in connection with the accompanying drawing, in which:

Figure 1 is a perspective view of the rear side of a stapled bow made on the stapling machine of Fig. 2.

Fig. 1^a is a front view, on reduced scale, of the bow of Fig. 1.

Fig. 2 is a side elevation of a stapling machine embodying the invention.

Fig. 3 is an enlarged side elevation of a portion of the machine shown in Fig. 1.

Fig. 4 is a stop motion view similar to Fig. 3 but showing the gauging device of the machine in operated position.

Fig. 5 is a detail vertical sectional view along the line 5-5 in Fig. 4.

Fig. 6 is a stop motion view similar to Fig. 5, but showing the die unit in operated position.

For purposes of exemplification, the invention has been shown and described herein as embodied in a machine (Fig. 2) adapted to form a hatband or ribbon in a flat decorative bow like that of Fig. 1 and which is suitable for example, for application to a man's hat. It will be understood, however, that the invention is in certain of its aspects also applicable to a wide variety of different forms of stapling machines. Accordingly, even though a particular embodiment of the invention has been shown and described in some detail, there is no intention to thereby limit the invention to such embodiment but, on the other hand, the appended claims are intended to cover all modifications and alternative constructions falling within the spirit and scope of the invention.

20 The decorative bow of Fig. 1 is formed from a band or strip of ribbon 10 folded upon itself to form inner and outer layers 10^a and 10^b for the bow with the end 10^c turned in so that the raw end is hidden between the layers and a complete loop formed. Transverse stiffeners, shown as fiber strips 11 and 12, serve not only to hold the ends of the bow against sagging but also facilitate the stapling of the band or ribbon in its necessary loop shape for the bow. The strip 25 11 is held to the inner bow layer 10^a at the closed end of the loop by tie hooks 14, while the other strip 12 is fixed to the inner bow layer 10^a, at what may be termed the open end of the loop, by staples 13. In each case, the staples extend only 30 through the adjacent stiffening strip and the inner layer of the bow so that when the bow is viewed from the front (as in Fig. 1^a) the staples are entirely hidden from view by the outer layer 10^b. If desired, of course, a center cross bar for 35 the bow may be added before it is applied to a 40 hat.

The tie hooks 14 are of a form disclosed and claimed in my copending application Serial No. 310,898, filed December 26, 1939. Each of these 45 tie hooks is formed from a generally U-shaped staple and one leg is clinched flat against the inner bow layer 10^a to clamp the same against the stiffening strip 11 while the other leg is bent 50 outwardly in a hook shape in order to serve as a means for attaching the bow to a hat. In fashioning the bow of Fig. 1, these tie hooks 14 are first secured in position and clamp the stiffening strip 11 in place. Thereafter, the bow of Fig. 55 1 is completed by the machine herein disclosed. To identify briefly the principal parts of the

machine (Fig. 2), it should be noted that it includes a stapler head 15 which may be depressed to clamp a portion of the ribbon material beneath it and to drive one or more staples through the material. Beneath the stapler head 15 is a die unit 16 against which the material is clamped and which serves to clinch the emerging ends of the staple legs, which have been driven through the material, into an accurately flattened position on the underside of the material which is being stapled.

Cooperating with the die unit 16 is a gauge, designated generally by the numeral 17, which is shiftable bodily away from the die unit 16 a selected distance so as to draw out, for a corresponding distance, the overlapping parts of the band or ribbon 10 which is wrapped around the die unit and the gauge. Thus, when the gauge 17 moves from the position of Fig. 3 to that of Fig. 4, it pulls the loop in the ribbon 10 out so that the inner and outer layers 10^a and 10^b of the loop are of selected length. By thus positively limiting the range of movement of the gauge, the point of overlap at which the ribbon end 10^c is to be stapled to the body or fillet of the ribbon is accurately determined for the formation of a bow of predetermined size and of the form of that of Fig. 1.

Turning now to a more detailed consideration of the elements of the machine, the stapler head 15 is of conventional form and is carried by a swinging arm 18 (Fig. 2) pivoted at 19 on a frame or bed 20 for the machine which also supports the inner end of the die unit 16. The arm 18 is yieldably urged to its upper or inactive position (shown in Fig. 2) by a compression spring 21. To drive the staple or staples into a portion of material positioned beneath the stapler head 15, one or more axially movable plungers 22 in the stapler head are utilized. This plunger is yieldably held in its retracted or inactive position by a heavy compression spring 23. Staples are supplied to the driving plunger 22 on successive actuations of the stapler head by a magazine (not shown) housed within the stapler head and arm 18. Magazines and staple driving heads of this general form are well known in the art and consequently further detail of description is believed to be unnecessary.

To swing the stapler head 15 downward into clamping engagement with the material to be stapled and to actuate the staple driving plunger or plungers 22, a manual operating lever 24 is provided (Fig. 2). This lever is pivoted at 25 on a bracket 26 projecting upwardly from the frame 20. A contractile spring 27 normally urges the operating lever 24 into a retracted position against a stop pin 28. When the lever 24 is swung in a clockwise direction (as viewed in Fig. 2) a wear plate 29 thereon contacts the head of the plunger or plungers 22. Since the spring 23 is stiffer than the spring 21, however, the pressure exerted on the head of the plunger 22 causes the arm 18 to swing downwardly until the stapler head 15 abuts against the material to be stapled which rests on the die unit 16 thus securely clamping the same in place. Thereafter, continued pressure on the plunger 22 causes it to move axially downward within the stapler head 15 and drive a staple (two staples and two plungers are used in the particular machine shown) into the material which is presented to it.

The die unit 16 is in general fashioned to clinch the legs of the staples into an accurately flattened configuration along the underside of

the material being stapled. Upon reference to Fig. 5, it will be seen that the staples 13 are initially U-shaped, conventional wire staples of this type being suitable for the purpose. After being driven through the overlapping portions of the ribbon 10 and stiffener strip 12, the legs 13^a and 13^b of the staples are bent into the form shown in Fig. 6.

The particular die unit 16 illustrated, includes a top plate 30 (Fig. 3) hereinafter referred to as a carrier pivoted by a rib 31 along its rear edge on a bottom plate 32 supported at one end on the frame 20 so as to project laterally therefrom into the path of the staple head 15. Both the carrier 30 and the bottom plate 32 are substantially rectangular in form and define a generally block-like structure. The pivoted carrier 30 is yieldably urged into its projected or uppermost position (shown in Figs. 3 and 4) by one or more compression springs 33, upward movement under the bias of these springs being limited by a stop pin 34 (Fig. 4) fixed to the bottom plate 32 and projecting through a registering aperture in the carrier 30. A recess 35 in the top of the carrier receives the head of the stop pin 34, the recess being of sufficient depth to allow the carrier to execute its full stroke without having the pin head project above the top surface of the same. The top surface of the carrier thus remains smooth and unobstructed at all times.

The foot of the stapler head 15 is notched out as indicated at 36 (Fig. 2) to accommodate the material placed on the top of the die unit 16. Directly beneath the staple driving plunger 22 in the head 15, a recess 37 (Fig. 4) is fashioned in the die unit carrier 30. This recess is positioned to receive the staple legs 13^a—13^b as they are driven through the ribbon 10 and stiffening strip 12. Within this recess 37 are located two sets of clinching dogs or dies 38—39 and 40—41 (Fig. 5). One of these sets of dogs acts on the legs of one of the staples 13 and the other set acts in identical manner on the legs of the other staple. Accordingly, a description of the action of one set of the clinching dogs will suffice for both.

The clinching dogs 38 and 39 are loosely pivoted by pins 42—43, respectively, on the die unit top plate or carrier 30. The adjacent ends of the dogs are relieved as shown (Fig. 5) so that they do not interfere with each other in their swinging movement about their pivots. The free ends of the dogs 38—39 rest on a wear plate 44 fixed to the stationary die unit bottom plate 32. Accordingly, when the carrier 30 is pressed downward, from its projected position of Fig. 5 to its retracted position of Fig. 6, the dogs 38—39 are swung upwardly about their pivots 42—43. This motion of the dogs is utilized to complete the clinching of the staple legs 13^a—13^b.

The upper surfaces of the dogs 38—39 are substantially flat, being inclined downwardly toward each other when in their initial position shown in Fig. 5. Consequently, as the staple legs 13^a and 13^b emerge from the underside of the stiffener strip 12 through which they have been driven, their paths are intercepted by the respective top surfaces of the dogs 38—39 so that the legs are deflected inwardly during the final portion of their advance through the material which they pierce. Continued downward motion of the stapler head 15 presses the carrier 30 downward so that the dogs 38—39 are finally swung into the position of Fig. 6. In this position their flat top surfaces are pressed against

the bottom of the stiffener strip 12. The result is that the staple legs 13^a—13^b are clinched by being bent inward in a precise right angle configuration without any humping or bulging at the point of bending. This precise clinching of the staples is particularly desirable in stapling a decorative bow of the form shown in Fig. 1, since it prevents any unsightly distortion of the outer layer 10^b of the bow by the underlying staple legs.

The gauge 17 embodies a generally rectangular block 45 (Fig. 3) dimensioned so that its top and bottom surfaces are arranged substantially in alignment with the top and bottom surfaces of the die unit 16. This block 45 is fixed on the forward end of a table 46 which is in turn mounted for sliding movement toward and away from the die unit 16 along a guideway fashioned on the machine frame 20. A contractile spring 47, anchored at its opposite ends to pins 48 and 49 fixed respectively on an extension 49^a (Fig. 5) of the bottom plate 32 and the table 46, serves to yieldably urge the gauge unit 17 toward the die unit 16. A recess 50 in the outer face of the block 45 is dimensioned to receive the previously attached stiffening strip 11 on the ribbon 10 so that the ribbon may be looped loosely about the gauge block 45 and projecting end of the die unit 16 in the manner shown in Fig. 3 with the closed end of the loop accurately located on the block 45 by the engagement of the strip 11 with the recess 50. Then to draw the loop in the ribbon out to the desired length it is simply necessary to pull the gauge unit 17 away from the die unit 16 by depressing a treadle 51 (Fig. 1), which is connected to the gauge unit carrier 46 by a cord 52 led over a pulley 53. Such outward movement of the gauge unit is limited by an adjustably positioned stop pin 54 (Figs. 1 and 3) which can be set in any one of a series of holes 55. The stop pin 54 is, of course, set at a point corresponding to the displacement of the gauge unit 17 required for pulling the ribbon out to a point where the end 10^c will be overlapped with the main portion of the ribbon just a sufficient distance for stapling.

In some instances it may be desirable to make one of the layers 10^a—10^b of the bow in Fig. 1 longer than the other. For this purpose a plate 56 (Fig. 3) is arranged for movement transversely of the ribbon wound around the gauge block. For this purpose, the plate is adjustably fixed in position on the forward face of the block 45 by a screw 57 passing through a vertical slot 58 in the plate. It will be evident that by shifting the plate up or down, the length of the portion of ribbon passing over the top of the die unit and gauge block between the attached stiffening member 11 and the point at which the staple 13 is to be driven can be readily adjusted. This adjustment, however, does not affect the length of the material passing around the under side of the unit, hence the inner and outer layers of the completed loop are non-uniform.

In the operation of the machine described above, the operator first places a fiber stiffening strip 12 on the die unit 16 above the clinching dogs 38—39 and 40 and 41 and against guide plate 59 secured to the unit. This guide plate serves to hold the strip exactly at right angles to the ribbon and locates it in proper position for stapling. A length of ribbon having the stiffening strip 11 previously stapled to it at a point proper for the length of bow which is desired is then procured. This length of ribbon is loosely

wound about the platen 16 and gauge unit 17 in loop formation as shown in Fig. 3. The stiffening strip 11 is, of course, placed in the recess 50 in the outer side of the gauge block 45. The gauge plate 56 is set so that the portion of ribbon 10^a which is led over it will bear a predetermined dimensional relation to the lower portion 10^b. Similarly, the stop pin 54 is set so that when the gauge unit 17 is pulled out against it, the lower portion of the loop 10^b will be pulled out to a point where the ribbon end section 10^c just underlies the stapler head 15 (Fig. 4). It will be understood that in ordinary practice a large number of identical bows are usually made in succession so that the adjustments of the gauge plate 56 and stop pin 54 are comparatively infrequent.

After the machine has been preliminarily adjusted in the manner described above, and the ribbon 10 wound loosely in loop formation, as shown in Fig. 3, the operator depresses the treadle 51. Such actuation of the treadle draws the gauge unit 17 outward against the stop pin 54 and the loop in the ribbon is drawn out taut in the configuration shown in Fig. 4. During this operation, the operator holds his fingers on the overlapping portions of the ribbon on top of the second stiffening strip 12 so as to keep both sides of the loop taut and properly positioned for stapling. Then the manual operating lever 24 is swung down so that the stapler head 15 is depressed into clamping engagement with the overlapped portions of the ribbon.

Upon continued depression of the operating lever 24, the plunger 22 drives the staples 13 through the overlapped portions of the ribbon and also through the stiffener strip 12. Continued pressure on the operating lever 24 finally causes the carrier 30 to be depressed so that the sets of dogs 38—39 and 40—41 are swung to the position of Fig. 6, as previously described, and the staple legs 13^a—13^b neatly clinched against the underside of the stiffener strip 12. Thereafter, the operator has only to release the operating lever 24 and treadle 51 which return automatically to their initial positions under the bias of the respective springs 27 and 47. The bow of Fig. 1, which is thus completed, may then be slipped from the die unit 16 and gauge unit 17 which project laterally free of the machine frame 20, and another portion of ribbon placed in the machine for stapling in the same manner.

I claim:

1. A stapling machine comprising, in combination, a movable staple driving plunger, an opposed die unit located beneath said plunger, a gauge member located adjacent said unit and adapted to receive a piece of ribbon or the like wrapped about said unit and said member in loop configuration and overlapped at a point beneath said plunger, and means for shifting said gauge member a selected distance from said unit to pull the ribbon out until a predetermined length thereof is comprised in the loop.

2. In a stapling machine, the combination with movable means for driving the legs of a staple through a strip of ribbon material and a stiffening member presented thereto, of a die unit for clinching the staple legs against the underside of the stiffening member, said die unit including an elongated carrier pivoted at one end and having its free end located in opposed relation to the staple driving means, staple clinching means supported in a recess in the free end of the carrier, guide means on said carrier for locating the

stiffening member with respect to the staple clinching means, means yieldably holding the carrier in a position to permit the staple legs to be driven through the material and the stiffening member, said carrier being movable with the driving means after the staple has been driven, and means operative in the movement of the carrier for actuating the clinching means to clinch the staple legs flat against the underside of the stiffening member.

3. A machine for forming loops in strips of ribbon material comprising, in combination, a stationary member, a movable member shiftable toward and from the stationary member, means yieldably holding said movable member closely adjacent the stationary member while a strip of ribbon material is wound around the members in loop formation, means for shifting the movable member away from the stationary member to pull the ribbon into a loop of predetermined length, and means for securing the overlapping portions of the ribbon together to close the loop.

4. A machine for forming loops in strips of ribbon material comprising, in combination, a stationary member, a movable member shiftable toward and from the stationary member, means yieldably holding said movable member closely adjacent the stationary member while a strip of ribbon material is wound around the members in loop formation, adjustable means for determining the limit position of the movable member, means for shifting the movable member to its limit position to pull the ribbon into a loop of predetermined length, and means for securing the overlapping portions of the ribbon together to close the loop.

5. A machine for forming loops in strips of ribbon material comprising, in combination, a stationary member, a movable member shiftable toward and from the stationary member, means yieldably holding said movable member closely adjacent the stationary member while a strip of ribbon material is wound around the members in loop formation, adjustable stop means for limiting the displacement of the movable member with respect to the stationary member, means for shifting the movable member into engagement with said stop means to pull the ribbon into a loop of predetermined length, and means for securing the overlapping portions of the ribbon together to close the loop.

6. A machine for forming loops in strips of ribbon material each having a stiffening member attached at a point corresponding to the closed end of the loop, said machine comprising, in combination, a pair of members one movable laterally toward and away from the other, means urging said members together while a strip of ribbon material is wound around the members in loop formation, one of said members having a recess adapted to receive the attached stiffening member, means for moving the shiftable member away from the other member to determine the final length of the loop, a gauge plate adjustably supported on one of said members for movement transversely of the ribbon wound thereon and operative to displace one side of the loop and thereby increase its length with respect to the other side of the loop, and means for securing overlapping portions of the ribbon together.

7. A machine for forming loops in strips of ribbon material each having a stiffening member attached at a point corresponding to the closed end of the loop, a pair of members one movable laterally toward and from the other,

means urging said one member toward the other while a strip of ribbon material is wound around the members in loop formation, said one member having a recess adapted to receive the attached stiffening member and thus prevent movement of the ribbon relative to that member, guide means on the other member for locating a second stiffening member to be secured to the ribbon adjacent the other end of the loop, means for moving said one member away from the other member to determine the length of the loop, a gauge plate supported on one of said members for movement transversely of the ribbon wound thereon to vary the length of ribbon between the stiffening members at one side of the loop.

8. A machine for forming closed loops in strips of ribbon material each having a stiffening member attached at a point corresponding to the closed end of the loop, said machine comprising, in combination, a pair of members one shiftable laterally away from the other to determine the length of a loop formed in a ribbon wound around the members with the stiffening member held in fixed relation to said one member, guide means mounted on the other member and located within the confines of the loop for holding a second stiffening member in predetermined relation to the ribbon, and means associated with said other member for stapling the overlapped portions of the ribbon and the second stiffening member together.

9. A machine for forming a loop in a strip of ribbon material having a stiffening member attached thereto at a point corresponding to the closed end of the loop, said machine comprising, in combination, a staple driving plunger, a staple clinching die unit located in opposed relation to said plunger, a gauge member supported for movement toward and from the unit, means yieldably holding said member closely adjacent the unit to permit the strip of ribbon material to be wrapped about the unit and the member in loop configuration, said gauge member having a recess in one side for receiving the stiffening member attached to the material, means for shifting said gauge member a selected distance from the unit to pull the ribbon into a loop of predetermined length, and means for operating said plunger to drive a staple through the overlapping portions of the ribbon at the open end of the loop, said die unit cooperating with the plunger to clinch the staple.

10. A machine for forming a loop in a strip of ribbon material having one stiffening member attached thereto at a point corresponding to one end of the loop, said machine comprising, in combination, a staple driving plunger, a staple clinching die unit located in opposed relation to said plunger, guide means on said unit for locating a second stiffening member in position to be secured to the ribbon adjacent the other end of the loop, a gauge member supported for movement toward and from the unit, means yieldably holding said gauge member closely adjacent the unit to permit a strip of ribbon material to be wrapped about the unit and the member, the second stiffening member and the gauge member, said gauge member having a recess in one side for receiving the first mentioned stiffening member, means for moving said gauge member away from the unit to pull the ribbon into a loop of predetermined length with the stiffening members located substantially at opposite ends thereof, and means for operating said plunger to drive a staple

through the overlapping portions of the ribbon and the second stiffening member, said die unit cooperating with the plunger to clinch the staple.

11. A stapling machine comprising, in combination, a plurality of members one shiftable laterally away from the other to determine the

length of a loop of ribbon or the like wound about the same, means located adjacent said other member for driving a staple through the overlapped portions of the ribbon, and means carried by said other member for clinching the staple.

SERAPHINE F. BAUWENS.
